HYDRAULIC PRESS AND SIMILAR APPARATUS

David Scialky, Paris, France

Application February 1, 1934, Serial No. 709,390
In France February 6, 1933

1 Claim. (Cl. 60—54.5)

The present invention concerns hydraulic presses and apparatus of this kind.

The object of the present invention is to provide means for mixing a certain amount of glycerine with the water of the press, these means being adapted to work in combination with said press.

A preferred embodiment of the present invention will be hereinafter described with reference to the accompanying drawing, given merely by way of example, and in which:

The only figure is an axial sectional view of a hydraulic press according to the present invention.

As shown by the drawing, the hydraulic press comprises, in the known manner, a cylinder 1 in which moves a piston 2 rigidly connected with a plunger 3. This plunger, which cooperates with packing members 4, 5, and 6 of any suitable structure for insuring a fluidtight fit, moves in a chamber 10 from which the liquid under pressure can flow out through outlet conduit 7. This plunger imparts the desired pressure to the liquid in chamber 10 and conduit 7, said pressure being transmitted to the organ that is subjected to the action of the press, through said liquid. Plunger 3 is actuated by injecting a fluid under pressure into the chamber 8 of cylinder 1.

Any leakage of water that may occur in the apparatus is compensated by the injection into vessel 10 of liquid coming from a reservoir 9 placed at a higher level, this injection taking place when plunger 3 is in the position shown in the drawing, that is to say in its position of rest. For this purpose, I provide at the end of plunger 3 ports 11 which, in the position of rest of said plunger, open into a chamber 12 located between packing members 5 and 6. Into this chamber 12 also opens a pipe 13 connected with tank 9 in which the pressure can be varied.

The axis of the apparatus is vertically disposed. It will be readily understood that, with such an arrangement, the air that accumulates at the upper part of chamber 10 is evacuated as soon as said chamber is brought into communication with tank 9.

As shown by the drawing, the liquid under pressure in the press can be utilized for acting on a piston 15 moving in a cylinder 16, this piston 15 being also subjected to the action of a return spring 18. The rod of piston 15 may for instance control the displacements of the movable electrode of an electric welding machine and exert the welding pressure. According to the present

invention, the stroke of piston 15, and therefore the stroke of the organ controlled by said piston, can be adjusted by varying the pressure under which the liquid that serves to compensate leakage is placed. For this purpose, I may for instance feed, through a pipe 17, a fluid under the desired pressure into tank 9. When the system is in the position of rest, if the pressure in the tank is varied, piston 15 moves in a downward direction. Therefore, in the course of its active stroke, this piston 15 will move a shorter distance.

When the liquid in the hydraulic press is a mixture of water with glycerine or any other suitable mixture, I may provide a tank 19 for the glycerine at the top of which air is trapped and compressed, said tank 19 being closed by a check valve 20, said tank 19 being connected with chamber 12 through a conduit. With such an arrangement, a certain amount of glycerine can be fed to chamber 10 for instance in the following manner: the parts being in the position shown in the drawing, the fluid pressure acting on tank 9 is raised until liquid from 13 is forced into tank 19, or at least into the conduit connecting said tank 19 with chamber 12. This liquid mixes with the glycerin present in this conduit and said tank. When the pressure acting on tank 9 is reduced, the fluid pressure at the top of tank 19 forces back the mixture thus formed into chamber 10.

According to my invention, I may connect with said chamber 10 an organ for controlling the pressure, said organ being shown at 22. This organ may for instance consist of a pressure gauge 22 having a contact 23 and a pointer 24 inserted in an electric circuit including for instance an alarm signal (such as a lamp 26) and a battery 25.

It should be well understood that the above described embodiments are only examples of how my invention can be carried out. For instance tank 9 is only a possible form of the source of liquid under pressure that is the essential feature of the device according to my invention. It might be replaced by any pipe containing water under pressure and, in this case, by acting on a pressure adjusting organ or a valve provided in said pipe, it would be also possible to vary the stroke of the organ controlled by the hydraulic press.

In a general manner, while I have, in the above specification, described what I deem to be practical and efficient embodiments of my invention, it should be well understood that I do not wish to be limited thereto as there might be changes made in the arrangement, disposition and form of

the parts without departing from the principle of my invention as comprehended within the scope of the appended claim.

What I claim is:

- 5 In combination, a system including two rigidly interconnected pistons of unequal surfaces and two cylinders for said pistons respectively, the piston of larger surface being adapted to be actuated by a fluid under pressure, a liquid filling 10 the cylinder of the piston of smaller surface, a movable member operative by the liquid pressure in said last mentioned cylinder, a liquid containing tank placed at a certain distance above said cylinders, means in the smaller piston for connecting said tank with the last mentioned cyl-

inder when said pistons are in the position of rest, a closed reservoir containing a liquid to be mixed with the liquid from said tank, means for connecting said reservoir with said last mentioned cylinder when the pistons are in the position of rest, and means for exerting an adjustable fluid pressure on the liquid in said tank, whereby the position of said movable member corresponding to the position of rest of said pistons can be adjusted, and it is possible, by varying said adjustable fluid pressure when the pistons are in the position of rest to introduce a certain amount of the liquid in said reservoir into said second mentioned cylinder.
